UNITED STATES PATENT OFFICE.

WILLIAM J. ADAM, OF NORWOOD, MASSACHUSETTS, ASSIGNOR TO PLIMPTON PRESS, OF NORWOOD, MASSACHUSETTS, A CORPORATION OF MASSACHUSETTS.

ELEVATING-TRUCK.

1,210,252.

Specification of Letters Patent. Patented Dec. 26, 1916.

Application filed November 28, 1913. Serial No. 803,613.

To all whom it may concern:

Be it known that I, WILLIAM J. ADAM, a citizen of the United States, residing at Norwood, in the county of Norfolk and State of Massachusetts, have invented certain new and useful Improvements in Elevating-Trucks; and I do hereby declare the following to be a full, clear, and exact description of the invention, such as will enable others skilled in the art to which it appertains to make and use the same.

The invention relates to that class of trucks in which the load is supported on a vertically movable table which may be raised to transfer the load to the truck or may be lowered to transfer the load from the truck to another support.

The object of the invention is to provide novel and improved mechanism for raising and lowering the table of this type of truck which will enable the load to be readily and conveniently handled with comparatively little exertion on the part of the operator.

A further object of the invention is to provide novel and improved means for connecting the table raising and lowering mechanism with its operating lever, so that the lever may be readily connected with or disconnected from the raising and lowering mechanism. This means is preferably so constructed and operated that the lever is not operative to effect the lowering of the table until the connecting means is set by the operator, thus avoiding any accidental or premature lowering of the table by manipulation of the operating lever.

To these ends the invention consists in the features of construction and combinations of parts hereinafter described and referred to in the claims.

The various features of the invention will be readily understood from an inspection of the accompanying drawings and the following detailed description of the truck illustrated therein.

In the drawings, Figure 1 is a plan view of a truck embodying the invention in its preferred form; Fig. 2 is a vertical sectional view on line 2—2, Fig. 1; Fig. 3 is a vertical sectional view on line 3—3, Fig. 1; Fig. 4 is a view similar to Fig. 3, showing the table in its raised position; Fig. 5 is a detail sectional elevation showing the means for operating the raising and lowering wedges; Fig. 6 is a similar view showing the parts in an-

other position; Fig. 7 is a plan view of the parts shown in Fig. 5; the table being removed; Fig. 8 is a front elevation of one side of the truck; and Fig. 9 is a sectional rear elevation showing one of the rear raising and lowering wedges and one of the rear supporting wheels.

As shown in the drawings, the truck carriage comprises the body frame 1 to which the rear axle 2 and front axle 3 are secured. The carriage is supported upon four wheels 4, the two rear wheels being mounted upon trunnions formed at the end of the rear axle 2 and the two forward wheels being mounted upon trunnions formed on steering knuckles 5 which are pivoted in the ends of the front axle. The steering knuckles are provided with arms 6 connected by a link 7. The link 7 is connected by a pin and slot connection 8 with a steering lever 9, the rear end of which is pivoted on the front axle 3, and the front end of which is connected to a tongue 10 by which the truck is propelled and its movements controlled. The vertically movable table of the truck comprises the side bars 11 which are connected by the front and rear cross bars 12 and 13. The table is guided so that it will move vertically by a vertical guide pin 14 secured in a boss formed at the center of the rear axle and fitting within a hole formed in a guide plate 15 secured to the under side of the cross bar 13 (Figs. 1 and 2).

The mechanism for raising and lowering the table comprises four wedges provided with inclined upper and lower edges and adapted to be moved longitudinally between rolls mounted upon the carriage and table respectively. The two front wedges 16 are formed on a wedge plate 17, and are arranged to move between rolls 18 mounted on the front end of the frame 1 and rolls 19 mounted upon the brackets 20 which are secured to the cross-bar 12 of the table. The brackets are provided with upwardly projecting posts 20 adapted to engage the load when the truck is run under it to properly position the truck with reference to the load. The rolls 18 and 19 engage the lower and upper inclined edges of the wedges 16, and are provided with flanges which form lateral guides to embrace the wedges and hold them against transverse movement, and also prevent transverse movement of the table. The front wedge plate 17 is connected by rods 21

with the rear wedges 22, and the rear wedges are held in fixed relation transversely by a cross-rod 23. The wedges and the connecting rods thus form a rigid frame which may be moved longitudinally in raising and lowering the table, and which itself moves vertically during its longitudinal movement. The rear wedges 22 are engaged by lower rolls 24 and upper rolls 25 mounted upon the rear end of the frame 1 and upon the under side of the cross-bar 13 respectively, the rolls being provided with flanges which form lateral guides to embrace the wedges and retain the wedge frame and table in proper relation to the carriage and to each other. The wedges are provided at their smaller ends with curved surfaces 26 forming stops for engaging the rolls and limiting the movement of the wedge frame in lowering the table. The front wedges 16 are also provided with recesses 27 at their larger ends which receive the rolls 18 and 19 when the table is raised and retain the wedge frame in the position into which it has been moved in raising the table. The retaining recesses may be formed in the rear wedges instead of in the front wedges, or both sets may be provided with these recesses.

The means for operating the wedge frame to raise or lower the table comprises a lever 28 pivoted to the front end of the frame 1 and provided with a socket for receiving the operating handle 29. The rear end of the lever extends laterally in both directions, and carries two rolls 30 arranged to engage the rear sides of two lugs or arms 31 which project inwardly from the wedges 16. When the lever 28 is swung from the position indicated in Fig. 2 to the position indicated in Fig. 4, the rolls 30 acting against the lugs 31 move the wedge frame toward the left, thus forcing the wedges between the rolls on the carriage and table, and lifting the table into the elevated position indicated in Fig. 4. When the wedge frame and table reach this position the rolls 18 and 19 enter the recesses 27 in the wedges 16 and lock the wedge frame and table in position. The lever 28 may now be swung up into the position indicated in Fig. 2, or otherwise manipulated without affecting the wedge frame and without disturbing the table.

The means for connecting the operating lever 28 to the wedge frame to effect the lowering of the table comprises a latch in the form of a bail 32 pivoted to the lugs 31 of the wedges 16 and arranged to move down back of the rear arm of the lever 28 when the lever is in the position indicated in Fig. 5. When the latch is raised the handle 29 may be moved up into vertical position without operating the wedge frame to lower the table, but when the latch is lowered it connects the rear arm of the lever 28 to the wedge frame so that the frame will be oper-

ated to lower the table when the handle 29 is raised. In the construction shown the connecting latch 32 is held normally in inactive position above the path of the lever 28 by a weight 33 pivoted to one of the lugs 31 and connected with the latch by a chain 34 or other connection. The weight is supported in normal position upon a stop 35. When the operator desires to lower the table he swings the lever 29 down into the position indicated in Figs. 5 and 6, and then throws the weight 33 forward into the position indicated in Fig. 6. This allows the latch 32 to drop down into active position. Now when the lever 29 is moved upward toward the position indicated in Fig. 2, the lever 28 will act upon the latch 32 and move the wedge frame toward the right until the rolls 18 and 19 are disengaged from the recesses 27. The weight of the table will then cause the wedge frame to move into its retracted position. As the wedge frame moves toward the right, the weight 33 will strike one of the roll carrying brackets on the cross bar 12, and will be swung back into the position indicated in Fig. 5, thus raising the latch 32 so that the lever 28 is automatically rendered inactive to lower the table. With this mechanism, the devices for raising and lowering the table are inactive to lower the table until set by the operator, and after having been set, are again rendered inactive by the lowering of the table. The retention of the table in its raised position until the load is to be transferred, or until the operator intentionally lowers the table, is insured.

Having explained the nature and object of the invention, and specifically described one form of mechanism in which it may be embodied, what is claimed is:

1. An elevating truck, having, in combination, a carriage, a vertically movable table, a front wedge plate provided with two wedges having upper and lower inclined edges, two rear wedges having upper and lower inclined edges, rods connecting the rear wedges to the wedge plate, a cross rod connecting the rear wedges, rolls on the carriage provided with flanges embracing the lower edges of the wedges, rolls on the table provided with flanges embracing the upper edges of the wedges, guiding devices for preventing longitudinal movement of the table, and means for moving the wedge frame longitudinally.

2. An elevating truck, having, in combination, a carriage, a vertically movable table, a vertically movable wedge frame provided with two rear and two front wedges having upper and lower inclined edges, rolls on the carriage engaging the under edges of the wedges and provided with flanges for preventing transverse movement of the frame, rolls on the table engaging the upper

- edges of the wedges and provided with flanges for preventing transverse movement of the table, and means for moving the wedge frame longitudinally.
5. 3. An elevating truck, having, in combination, a carriage, a vertically movable table, a vertically movable wedge frame provided with two rear and two front wedges having upper and lower inclined edges, one set of wedges being provided with locking recesses at their large ends, rolls on the carriage engaging the under edges of the wedges and provided with flanges for preventing transverse movement of the frame, rolls on the table engaging the upper edges of the wedges and provided with flanges for preventing transverse movement of the table, and means for moving the wedge frame longitudinally.
10. 4. An elevating truck, having, in combination, a carriage, a vertically movable table, a vertically movable wedge frame provided with wedges having upper and lower inclined edges, rolls on the carriage and table respectively between which the wedges play, an operating lever normally connected to move the wedge frame in a direction to raise the table, and means under the control of the operator for connecting the lever to move the frame in the opposite direction.
15. 5. An elevating truck, having, in combination, a carriage, a vertically movable table, mechanism for raising and lowering the table including a wedge frame provided with a projection, an operating lever provided with an arm engaging the projection to move the frame in a direction to raise the table, and normally inactive means adapted to be set by the operator for connecting the wedge frame with the lever to move the frame in the opposite direction.
20. 6. An elevating truck, having, in combination, a carriage, a table, mechanism for raising and lowering the table, including a reciprocating frame, an operating lever, devices normally connecting the operating lever and said frame whenever the table is in lowered position, and devices which are normally inactive and are adapted to be set by the operator for connecting said operating lever with said frame when the table is in raised position.
25. 7. An elevating truck, having, in combination, a carriage, a table, mechanism for raising and lowering the table, operating means for actuating said mechanism to raise the table, a device adapted to be set by the operator for connecting said means with said mechanism to lower the table, and means for automatically rendering the connecting device inoperative by the movement of the parts in lowering the table.
30. 8. An elevating truck, having, in combination, a carriage, a table, mechanism for raising and lowering the table including a reciprocating frame, a projection on the frame, an operating lever having an arm engaging the projection to move the frame in a direction to raise the table, and a latch adapted to be set by the operator for connecting the lever to move the frame in the other direction.
35. 9. An elevating truck, having, in combination, a carriage, a table, mechanism for raising and lowering the table including a reciprocating frame, a projection on the frame, an operating lever having an arm engaging the projection to move the frame in a direction to raise the table, a latch adapted to be set by the operator for connecting the lever to move the frame in the other direction, and means for rendering the latch inoperative in lowering the table.
40. 10. An elevating truck, having, in combination, a carriage, a vertically movable table, mechanism for raising and lowering the table including an operating lever having an arm, a reciprocating frame having a shoulder arranged to be engaged by the arm on the operating lever, and a latch on the frame movable into and out of position back of the arm of the operating lever.
45. 11. An elevating truck, having, in combination, a carriage, a vertically movable table, a wedge frame comprising a front wedge plate between the carriage and table provided with two wedges having upper and lower inclined edges, two rear wedges between the carriage and table having upper and lower inclined edges, rods connecting the rear wedges to the wedge plate, and a cross rod connecting the rear wedges, rolls on the carriage on which the lower edges of the wedges rest, rolls on the table resting on the upper edges of the wedges, lateral guides at the sides of the rolls embracing the wedges, guiding devices for preventing longitudinal movement of the table, and means for moving the wedge frame longitudinally.
50. 12. An elevating truck, having, in combination, a carriage, a vertically movable table, a vertically movable wedge frame between the carriage and table provided with two rear and two front wedges having upper and lower inclined edges, rolls on the carriage engaging the under edges of the wedges, rolls on the table engaging the upper edges of the wedges, lateral guides at the sides of the rolls embracing the wedges to maintain the wedge frame, table and carriage in proper relation, and means for moving the wedge frame longitudinally.
